POWER SYSTEM FOR COMBINED GATHERING AND LOADING MACHINES

Einar M. Arentzen, Franklin, Pa., assignor to Joy Manufacturing Company, Franklin, Pa., a corporation of Delaware

Application June 12, 1935, Serial No. 26,182

11 Claims. (Cl. 198—10)

This invention relates to an improved power system for an automotive combined gathering and conveying machine, and especially to a machine of this type for use in the coal mining industry, and which is adapted to travel upon the floor of a mine or other surface from which material is to be gathered; to gather said material as the machine travels and to convey and deliver same to a point rearwardly of the machine. Such a machine, in order to attain a maximum of efficiency, utility, and practical accomplishment, must be supplied with an automotive, tractive mechanism, whereby the gathering head may be moved forwardly, maneuvered laterally in either direction, retracted from the material upon which it is operating. In case the coal or other material has been blasted or otherwise loosened, thus adapting it to feed by gravity to the gathering head, and when an obstruction or unwieldy mass of material is encountered, the tractive elements of the power system must be capable of being quickly stopped, reversed or swerved laterally into the most effective gathering position.

As an example of the state of the art which has thus far been attained in machines of this class, reference is made to U. S. Patent No. 1,619,260, dated March 1, 1927.

The machine to which this patent relates is equipped with one motor as its driving power for all the operative sub-organizations, including the tractive, the gathering, and the conveying devices; said tractive devices being supplied with a differential gear and a brake mechanism whereby steering functions are accomplished.

It is the object of this invention to supply a power system for machines of this class whereby greater facility and speed of operation, increased output, a reduction of power requirement, and a wider field of use, especially in thinner seams of coal, are attainable.

The particular construction and manner in which each of these objects is attained will be pointed out in due order in the following specification, and is fully illustrated in the accompanying drawings in which:

Fig. 1 is a schematic view of said power system.

Fig. 2 is a plan view, which upon one side, shows one side of the gathering and conveying organization removed to illustrate the opposite side of the truck thereunder.

Fig. 3 is a side elevation of the adjacent side of Fig. 2.

Fig. 4 is a transverse section through the gath-

ering head at the point indicated by the line IV—IV of Fig. 2, the gear-box which contains the elevator and gathering arm gears being shown in elevation upon the right hand side; said box and a portion of the gearing therein being shown in central, vertical section upon the left hand side of this view.

Fig. 5 is a right side view of the gathering apron with a portion of the corresponding gear-box shown in vertical section.

Fig. 6 is a vertical section on line VI—VI of Fig. 1.

Fig. 7 is a side elevation of the combined gear and sprocket which drives the caterpillar traction chain, and a half-section and half side view of the driving pinion for said sprocket, which is mounted upon the power delivery shaft of each of the driving motors.

Fig. 8 is a schematic wiring diagram of the electrical system of this invention.

Fig. 9 is a plan view of the casing which contains the four-point, reversing, two-drum controllers relating to the two independently driven motors which drive the tractive organizations respectively, a portion of the cover being removed to reveal underlying details to view; other parts of this figure are drawn in section to expose to view the two shafts whereby the drums of these controllers are respectively operated.

Fig. 10 is a wiring diagram showing in detail the wiring system for the four motors which constitute the power system of this invention.

Fig. 11 is a symbolic wiring diagram of the four-point, reversing, right hand, tractor-drum detail.

Fig. 12 is a symbolic, electrical wiring diagram of the head motors, which are adapted to series start and parallel run.

The conveyor shown in the drawings is clearly illustrated in U. S. Patent No. 1,785,402, dated December 16, 1930.

The power system illustrated in said drawings embraces the details which are arranged and operate as follows:

Referring to Fig. 1, the right hand end of this view corresponds to the rearward end of the machine; adjacent this rearward end is mounted a right hand motor 1 and a left hand motor 2, the axes of which are in alignment and extend transversely of the chassis in the corresponding side members of which they are respectively mounted and rigidly carried; these motors are equipped with self-contained speed-reducing gearing, and are adapted, by means of suitable, individual combined switch and drum-controllers to be in-

dependently operated in either the same or in opposite directions. The power-delivery shaft 3 of motor 1 extends outwardly from the outer end of the motor casing and has rigidly affixed thereto a pinion 4, adapted to mesh with and to directly drive a gear-sprocket wheel 5, which in turn serves as a sprocket to drive a caterpillar tractive mechanism or chain 6.

In like manner, the outer end 7 of the power-delivery shaft of motor 2 extends outwardly from the casing of this motor and has rigidly affixed thereto a pinion 8 arranged in mesh with a gear-sprocket wheel 9, which, in turn engages with and drives the caterpillar chain 10. In Fig. 1 of the drawings, the outer end of the motor casing is shown in central, longitudinal section for the purpose of exposing the speed-reducing gearing to view. Inasmuch as such self contained speed-reducing gearing is not new, and is well known to electrical engineers, a description of the details thereof is deemed unnecessary.

Said gear-sprocket wheels are each carried by their respective side members 11 and 12 of the chassis, as clearly shown in Fig. 6. From these sprockets the respective caterpillar chains extend around idler pulleys 13 and 14, respectively, which are positioned at the front end of the chassis; they are mounted upon a transversely-extending shaft 15 which is adapted to have movement longitudinally of the chassis; each end of said shaft is supplied with and engaged by a tension device 16 whereby said caterpillar chains are automatically retained in a suitable taut condition.

For the purpose of operating the gathering arms which are carried by the gathering head, shown in side elevation in Fig. 5, two motors 17, 17 are employed; these motors are arranged in parallel relation, their axes extending longitudinally of the chassis and transversely to the axes of said traction motors 1 and 2, one at each side of the gathering head; they are interconnected for joint operation in a manner which will presently be set forth, so that they operate in coordinated unison; because of this characteristic, corresponding members of this power organization will be referred to by identical reference letters.

The forward end of the power-delivery shaft 18,—see Fig. 5,—extends through the motor casing and is connected by means of a suitable coupling 19 to a bevel pinion 20 which meshes with and drives a bevel gear 21, to the upwardly-extending end of a stubshaft 22 of which, is operatively, rigidly mounted a crank-disk 23; this disk is equipped with an upwardly-extending crank pin 24 for engagement with and actuation of a gathering arm 25. Said gear and pinion are suitably enclosed in a gear casing 26, in which is mounted a second bevel pinion 27 that meshes with and is driven by said gear 21; the stub shaft 28 of this pinion,—see Fig. 4,—is disposed inwardly toward the center of the machine at an angle of 90 degrees to the axis of pinion 20, and operatively engages a transversely-extending hollow shaft 29 which has formed integrally therewith a sprocket 30, which is adapted to drive the conveyor chain 31 and the thereto attached flights 32,—see Fig. 1; this conveyor chain travels longitudinally of the machine and delivers the gathered material rearwardly thereof.

The mechanical elements of my improved power system having thus been pointed out, reference will now be made to the electrical motors and the method and system of their operation and control.

All four of the motors employed are substantially identical in construction and power rating, and for the purposes of this specification it may be stated by way of illustration, that a 250 volt, direct current is used, which is supplied by a trailing cable 32, connected to and leading from any suitable source of current.

The service end of said trailing cable 32 enters the casing 33 of a simple drum switch which is adapted by means of a starting switch 35 to so control the current passing therefrom, through the conductors 34, 34 to the gathering head motors 17, 17, that series starting of said motors is caused and thereafter parallel operation of the motors takes up their load operation.

A conductor 36 leads from said casing 33 to the casing 37 of a four-point, reversing drum controller of well known construction, in which said current is controlled and through which it passes as indicated in the wiring diagrams of Figs. 8, 10 and 11; from said casing, a conductor 38,—see Fig. 1,—leads to each traction motor 1 and 2.

Referring especially to Fig. 9 of the drawings, it is shown that the controller drums R, L, are selectively operable at will, in either direction, also separately, either in the same direction or reversely by means of the levers R', L', these levers being shown in Figs. 1, 3, and 6.

Within the off-set chamber 39 of the casing 31 are mounted the sprockets R'', L''; sprocket R'' is mounted upon a rotative hollow shaft 40, which extends transversely of the chassis and axially through the axle 41 of the sprocket 5; to the outer end of this shaft is actuatively secured said lever R'; the sprocket L'' is rigidly attached to the solid shaft 42 which extends through said hollow shaft 40, and is equipped at its outer projecting end with an actuatively-attached lever L'. Said levers and the switch 35 are in such proximity to each other as to be readily, simultaneously manipulated by the operator of the machine when standing at an intermediate point.

Referring to Fig. 3 or 6, when said levers L' and R' are in vertical position, the current is shut off; when they are actuated rearwardly, the machine runs in a corresponding direction; when they are actuated into their forward position, the machine is propelled in the forward direction; as previously stated, the levers may be moved in opposite directions,—which is termed the 100 per cent steering direction, and the machine is caused to turn pivotally, the pivotal point being intermediate the center point, both laterally and longitudinally of the caterpillar treads, and when either lever is moved (singly) in either direction, a 50 per cent steerage results.

The electrical connections and circuits are so arranged in this traction motor system that the motors may be operated either in unison, as when the tractive elements are propelling the machine either directly ahead or rearwardly; they may be operated separately, as when the machine is being turned by one tractive element, the other element being the pivotal point; one tractive element may be operated in one direction, and the other element reversely thereto, as when the machine is being thus turned and the pivotal point is intermediate said elements; in the dirigible operation of the loader, as when laterally directing the gathering head to the right or to the left, into actuative gathering relation to the material being gathered, the motors and their respective tractive organization may be selec-

tively operated in either direction—whereby the maneuvering of the gathering arms into gathering relation to said material is greatly facilitated. Said facilitation is due to the fact that, if the gathering head is to be moved to the right, this may be done by operating either the right hand tractive equipment in the rearward direction, or the left hand tractive equipment in the forward direction, in which case one of said organizations 5 will be inactive, and the gathering head in the respective cases will be caused to occupy a different position relative to the material to be gathered. Dirigibility of the loader when travelling about the mine, from place to place,—a function 10 which is aptly termed “flitting”—is accomplished with a high degree of facility, flexibility, and accuracy as to the objective positioning point.

Having pointed out the mode of operation of 20 my improved power system, it is in order to state the novel and improved advantages attained thereby, which are:

1. Saving of both time and power and greater 25 ease and accuracy of placement in negotiating the gathering head of the machine both laterally and longitudinally into gathering relation to the material to be gathered.

2. The elimination of differential gearing and 30 its necessarily associated brake accompaniment, heretofore used in causing the steering of automotive loading machines, and to secure a consequent material reduction of power in the performance of this function.

3. The production of a much lower loading 35 machine by the use of a plurality of small motors, and the consequent possibility of operating in thinner seams of coal from which mechanical loading has heretofore been excluded.

4. A decided simplification of transmissive 40 equipment and reduction of occupied space by the incorporation of speed-reducing and transmissive gears within the casing of the motor.

5. A greater degree of accessibility, especially to 45 the gathering motors, by their transferral from within the frame of the chassis to the outer, lateral limits of the gathering head.

6. A greater simplicity, accessibility, ease and 50 certainty of manipulation of the control levers.

7. A much more uniform distribution of operative 55 strains throughout the whole structure of the machine, which is attained through the symmetrical arrangement of the four motors with respect to the fore and aft axis of the machine, and the fact that all of said motors are disposed below the line of travel of the conveyor flight.

I claim the following:

1. In a combined gathering and conveying machine of the type which includes a chassis 60 frame, a tractive mechanism of the caterpillar type on each side thereof including a driving sprocket in direct driving relation with the chain thereof, a conveyor mounted upon said chassis frame and extending rearwardly to provide a delivery section, and a gathering organization arranged at each side of and adapted to move material onto the forward end of said conveyor, each gathering organization including a driving gear therefor and said conveyor having a driving 65 member driven jointly by the driving gears of

said gathering organizations, the combination therewith of a power system for said combined gathering and conveying machine whose motive mechanism is composed of four electrical motor units, two of said motor units being disposed adjacent and directly connected to said driving sprockets and two of said motor units being disposed adjacent and directly connected to the driving 5 gears of said gathering organizations.

2. A combined gathering and conveying machine 10 according to claim 1 wherein the four motor units are symmetrically arranged with respect to the fore and aft axis of the machine.

3. A combined gathering and conveying machine 15 according to claim 1 wherein each of said four motor units includes a driving shaft and a gear mounted thereon coaxially with the motor and in mesh with a driving sprocket of said tractive mechanisms or a driving gear of said gathering organizations.

4. A combined gathering and conveying machine 20 according to claim 1 wherein each of said four motor units is a self contained unit composed of a motor and a train of reducing gears 25 contained within a common casing.

5. A combined gathering and conveying machine 30 according to claim 1 wherein all of said four motor units are alike in structure and size.

6. A combined gathering and conveying machine 35 according to claim 1 wherein the two motor units connected to said driving sprockets are horizontally aligned and lie below the level of said conveyor.

7. A combined gathering and conveying machine 40 according to claim 1 wherein the two motor units connected to said driving sprockets are aligned horizontally and the two motor units connected to said driving gears for the gathering organizations have their axis disposed at right angles to said first named motors.

8. A combined gathering and conveying machine 45 according to claim 1 wherein all four motor units are disposed below the level of said conveyor.

9. A combined gathering and conveying machine 50 according to claim 1 wherein the two motor units connected to said driving sprockets are horizontally aligned and disposed below the level of said conveyor and the two motor units connected to said driving gears for the gathering organizations have their axis at right angles to said first named motors and disposed below the level of said conveyor.

10. A combined gathering and conveying machine 55 according to claim 1 wherein said four motor units have control mechanism disposed at a single station at the side of the machine and providing selective or concurrent operation of said motor units.

11. A combined gathering and conveying machine 60 according to claim 1 wherein said two motor units connected to said gathering organizations have a control mechanism for starting or stopping the same and said two motor units connected to said tractive mechanisms have selective control mechanism for rotating either or both of said motors in forward or reverse directions, or stopping the same.
